RECORD EDGING LATHE

Frank G. Volkel, Los Angeles, Calif., assignor to
 Volkel Bros. Machine Works, Los Angeles,
 Calif., a corporation of California

Application August 10, 1946, Serial No. 689,675

6 Claims. (Cl. 51—237)

1

My invention relates generally to lathes and more particularly to lathes for holding flat disc-shaped objects, and has as a principal object to provide a tool suitable for holding and rotating a phonograph record while such a record is being shaped to circular form.

In the process of manufacturing phonograph records, the discs are molded in presses from which they emerge with a thin peripheral lip or flange which must then be removed. The fragility of the discs requires that they be held both firmly and gently during the grinding operation necessary to remove the lip, and that the force with which they are clamped shall be applied softly. As the operation is a short one, it is desirable to have a lathe which will engage and disengage the discs rapidly and yet not subject them to positive forces applied in haste by the operator.

It is, therefore, a further object of my invention to provide a record edging lathe in which a record may be clamped by a gentle force, pneumatically, and therefore impositively, applied.

It is another object of my invention to provide a lathe which will automatically begin the rotation of a phonograph record as soon as sufficient pressure has been applied to the record to clamp it firmly, and which will desist from such rotation as soon as such pressure has been released.

Still another object of my invention is to provide an enclosure within which a record may be safely ground which shall be closable and openable by the means actuating the clamping of the record and the rotation thereof simultaneously with the beginning and end of such rotation, thereby effecting further time-saving in the setting up of the operation.

I accomplish the foregoing objects and others which will appear hereinafter in a manner fully set forth in the following description of a preferred embodiment of my invention and illustrated in the accompanying drawings, of which:

Fig. 1 is a plan view of a record edging lathe according to my invention;

Fig. 2 is a longitudinal sectional view showing the lathe in open, or non-operative, position;

Fig. 3 is a transverse sectional view on the line 3—3 of Fig. 2; and

Fig. 4 is a view similar to Fig. 2, but showing the lathe in closed, or operative, position.

Having reference now to the details of the drawings, 11 is a base suitable for mounting on a bench, on which are secured a clutch housing 12 and a diaphragm housing 13. Extending from the clutch housing 12 is a shaft housing 14 in

2

which a shaft 15 is rotatable in bearings 16. A hollow shaft 17 is secured to the clutch housing 12 and extends thereinto to encompass one end of the shaft 15 and supports, rotatably on a bearing 18, a drive pulley 19 concentric with the shaft 15. Secured to the shaft 15 is a two-faced clutch member 21, having one clutch face 22 adapted to engage a coacting clutch plate 23 on the drive pulley 19 to impart rotary movement to the shaft, 10 and a second brake face 24 engageable with the clutch housing 12 to provide a brake for such movement. A thrust bearing 25 engages the end of the shaft 15 and is held by a spring 26 and plug 27 so as to permit the shaft to reciprocate 15 to bring the clutch member 21 to bear either against the clutch plate 23 or the clutch housing 12, with the spring 26 urging the shaft in the latter direction. Grease guards 28, which may be of conventional cap and retaining spring design, are provided to retain grease in the bearings 16 and 18 and to exclude dust therefrom.

The diaphragm housing 13 clamps the edges of a diaphragm 31 secured by plates 32 to a reciprocating shaft assembly 33. Air to move the diaphragm 31 and shaft assembly 33 is admitted 25 to the diaphragm housing 13 through an air conduit 34 provided with suitable operating valves, not shown. The shaft assembly 33 is urged by a spring 35 to react against the movement imparted 30 thereto by the diaphragm 31, and is held against rotary movement by a set screw 36 sliding in a keyway 37. A cup and spring packing 38 similar to grease guards 28 seals the diaphragm housing 13 to the shaft assembly 33.

The shaft 15 has secured thereto a disc 41 with a facing 42 of hard felt or similar resilient material, and has an arbor 43 extending through the facing 42 and adapted to engage the center hole of a phonograph record 44. A disc 45 having a similar resilient facing 46 is rotatably mounted on the shaft assembly 33 by a bearing 47. The bearing 47 is retained on the shaft assembly 33 by a bolt 48 and washer 49, and the disc 45 is pressed on the outer race of the bearing and retained thereon by a snap ring 51. A grease guard 52 is provided to protect the bearing 47. The disc 45 and facing 46 have an orifice 53 to receive the end of the arbor 43.

To enclose the record 44 and to protect the operator from particles flying therefrom while the record is being edged, I provide a bisected enclosure 54 formed by two coacting dust guards 55 and 56, of which the former is secured to the shaft housing 14 so as to be immovable and the latter is secured to the shaft assembly 33 so as to

be reciprocable therewith. Peripheral rings 57 of soft rubber or like material are provided on each of the dust guards 55 and 56 to form a yielding closure therebetween when the dust guards are brought together. Each of the dust guards 55 and 56 and their respective peripheral rings 57 are cut away as illustrated at 58 in Figs. 1 and 3, to form an orifice 59 providing access to the record 44 through the enclosure 54. To exhaust dust and chips from the enclosure 54, the immovable dust guard 55 has a conduit 60 connected thereto and leading to a suction pump (not shown) the air for transporting the dust entering through the orifice 59.

To operate the lathe from the starting position illustrated in Figs. 1 and 2, the operator places a record 44 upon the arbor 43 and operates the controls on the conduit 34 to admit air to the diaphragm housing 13. The diaphragm 31 will then move the shaft assembly 33 against the compression of the spring 35 to bring the facing 46 of the disc 45 into contact with the record 44, clamping the record 44 between the confronting facings 42 and 46, and bringing the peripheral ring 57 of the dust guard 56 into yielding contact with the coating ring of the dust guard 55 to form the enclosure 54. Further movement of the shaft assembly 33 presses the shaft 15 and thrust bearing 25 against the compression of the spring 26, causing the brake face 24 of the clutch member 21 to break away from the clutch housing 12 and the clutch face 22 to engage the clutch plate 23 of the drive pulley 19. As the drive pulley 19 is freely rotating on the bearing 18, contact of the clutch faces 22 and 23 will cause rotation of the shaft 15 with consequent rotation of the record 44 and the discs 41 and 45 clamped thereto, the disc 45 being free to rotate upon the bearing 47. The operator may then insert a suitable tool through the orifice 59 to grind the edge of the record 44. Dust and chips from the grinding will be exhausted through the conduit 60.

When the grinding operation is completed, the operator changes the controls on the air conduit 34 to release the air in the diaphragm housing 13 through the conduit 34. The spring 35 will then return the shaft assembly 33 to its original position, opening the enclosure 54 and withdrawing the disc 45 from its clamping position upon the record 44. The spring 26 will return the shaft 15 to its original position, releasing the clutch face 22 from the clutch plate 23 and bringing the brake face 24 to bear against the clutch housing 12, braking the rotation of the shaft and of the record 44. As the return action of the spring 26 occurs at the earliest possible moment and requires less longitudinal movement than that required to move the end of the arbor 43 from the orifice 53, the rotation of the record 44 will be checked without danger of the record 44 flying from the arbor 43. In fact, due to the facings 42 and 46 being under compression and requiring material movement of the shaft assembly 33, and as this movement is lessened in effect by the follow-up movement of the shaft 15, the braking effect of the brake face 24 is transmitted through the record to the disc 45 and the rotation of the disc 45 is braked before the clamping on the record 44 is released.

Numerous modifications may be made in the application of the principles of the present invention, and the scope of the appended claims is not to be considered as limited to the herein delineated form of apparatus.

I claim as my invention:

1. In a lathe, a shaft mounted to be rotatable and longitudinally movable; a drive pulley concentric with said shaft and rotatable independently thereof; a first clutch face on said pulley; a second clutch face on said shaft engageable with said first clutch face by longitudinal movement of said shaft in one direction to effect rotation of said shaft; brake means on said shaft actuatable by movement of said shaft in the opposite direction; a spring urging said shaft in said opposite direction whereby said brake means are normally activated; a first disc having a face of material secured to said shaft and rotatable therewith; a support aligned with said shaft and mounted to be movable in said one direction and said opposite direction; a second disc rotatably mounted on said support and having a face of material adapted when moved into adjacency with said first disc to clamp a phonograph record therebetween; a pin extending from one of said discs, said pin being of such length as to pass through said record; a second spring urging said support in said opposite direction; and means for moving said support, in said one direction to bring said discs to adjacency and then to move said shaft in said one direction, whereby said brake means are inactivated and said first and said second clutch faces are engaged.
2. In a lathe, a pair of discs mounted in confronting relation and adapted to form clamping jaws; a piston supporting one of said discs, said one disc being rotatably mounted thereon; a housing; a shaft rotatably mounted in said housing and supporting the other of said discs; clutch means for effecting rotation of said shaft; means acting on said piston for moving said one disc into clamping engagement with said other disc; a pair of dust guards forming a bisected enclosure for said discs, one of said guards being secured to said housing and the other of said guards being secured to said piston, whereby said enclosure is closable and openable by the movement of said piston, said enclosure having an orifice providing access to said discs; and a conduit connected to said first defined guard for exhausting said enclosure.
3. In a lathe, axially aligned supporting members, one of which is reciprocable only and the other of which is rotatable and reciprocable; clamping members mounted in confronting relationship on said supporting members and adapted to grasp a work piece when moved thereby to adjacency; that clamping member mounted on said first defined supporting member being rotatable with respect thereto; means for reciprocating said first defined supporting member; means actuatable by said last mentioned means for rotating said second defined supporting member; and a bisected enclosure for said clamping members having one part secured to said first defined supporting member and reciprocable therewith to effect closing and opening of said enclosure.
4. In a lathe of the character described, the combination of: a first disc and a second disc in confronting relation and adapted to form clamping means to engage opposite sides of a record; a housing; a shaft rotatably mounted in said housing; and supporting said first disc; a support supporting said second disc for rotation on the axis of said shaft; clutch means for effecting rotation of said shaft; means acting on said support for moving said second disc into clamping relation to said first disc; and a pair of

guards forming a bisected enclosure for said discs, one of said guards being secured to said housing and the other of said guards being secured to said support, whereby said enclosure is closable and openable by movement of said support, said enclosure having an opening providing access to said discs.

5. In a lathe of the character described, the combination of: a first disc and a second disc in confronting relation and adapted to form clamping means to engage opposite sides of a record; a housing; a shaft rotatably mounted in said housing and supporting said first disc; a support supporting said second disc for rotation on the axis of said shaft; clutch means for effecting rotation of said shaft; means acting on said support for moving said second disc into clamping relation to said first disc; a pair of guards forming a bisected enclosure for said discs, one of said guards being secured to said housing and the other of said guards being secured to said support, whereby said enclosure is closable and openable providing access to said discs; and a conduit connected to the interior space of said enclosure through which an exhaust effect may be applied to said interior space of said enclosure.

6. In a lathe of the character described, the combination of: first and second engaging means for engaging the opposite sides of an article to be turned; means for supporting said engaging

means for rotation; drive means for rotating at least one of said engaging means; and a pair of guards forming a closure for an article held by said engaging means, respectively secured to said supporting means and being relatively movable toward each other and apart so as to close and open said enclosure, at least one of said guards having an annular wall of yieldable material to engage the other of the guards when said guards are relatively moved toward each other so as to close the enclosure.
